D. B. WILLIAMS.
TYING DEVICE FOR BUNDLING PURPOSES.
APPLICATION FILED DEO. 10, 1910.

Patented Sept. 26, 1911.

UNITED STATES PATENT OFFICE.

DICK B. WILLIAMS, OF NEW ORLEANS, LOUISIANA, ASSIGNOR OF ONE-SIXTH TO WILLIAM F. WALL, OF NEW YORK, N. Y., AND ONE-SIXTH TO CLARENCE P. LANDRETH, OF PHILADELPHIA, PENNSYLVANIA.

TYING DEVICE FOR BUNDLING PURPOSES.

1,004,514.

Specification of Letters Patent. Patented Sept. 26, 1911.

Application filed December 10, 1910. Serial No. 596,780.

To all whom it may concern:

Be it known that I, DICK B. WILLIAMS, a citizen of the United States, residing at New Orleans, in the parish of Orleans and 5 State of Louisiana, have invented certain new and useful Improvements in Tying Devices for Bundling Purposes, of which the following is a specification.

The present invention relates in general 10 to devices for binding bundles of laths, staves, lumber, and the like, with wire drawn from a continuous reel, and the invention has more particular relation to a novel and advantageous means for severing the wire 15 and twisting the ends thereof.

The object of the invention is to provide a wire cutting and twisting mechanism which is very simple and inexpensive in its construction, which can be readily applied 20 to any of the bundling machines in common use, and which will act in a positive and reliable manner to sever the wire and twist the ends thereof securely together so as to bind the bundle with the wire.

25 A further object of the invention is the provision of a device of this character which is very quick in its action and will enable an operator to bind a large number of bundles in a comparatively short period of time.

30 With these and other objects in view, the invention consists in certain combinations and arrangements of the parts as will more fully appear as the description proceeds, the novel features thereof being pointed out in 35 the appended claims.

For a full understanding of the invention, reference is to be had to the following description and accompanying drawings, in which:—

40 Figure 1 is an end view of a conventional form of bundling machine having the improved wire cutting and twisting device applied thereto. Fig. 2 is a top plan view of the wire cutting and twisting device. Fig. 3 is a bottom view of the same. Fig. 4 is an end view of the wire cutting and twisting device, portions being broken away and shown in section. Fig. 5 is a side view of the device, portions being broken away, and 45 Fig. 6 is an enlarged detached perspective view of the rotary cutting and twisting head.

Corresponding and like parts are referred

to in the following description and indicated in all the views of the drawings by the same 55 reference characters.

For the purpose of illustration the invention has been shown and will be described as employed in connection with a machine for bundling laths or the like, although it will 60 be understood that the invention can also be employed wherever such a device would be desirable.

The bundling machine comprises a frame 1 having a pair of oppositely disposed bundling arms 2 mounted thereon, the usual mechanism being provided whereby the bundling arms can be operated through the medium of a foot lever 3. A reel 4 of wire is shown as mounted upon one side of the 70 bundling machine toward the base thereof, and the wire which is drawn from this reel passes between a pair of guide rollers 5 upon one of the bundling arms 2.

The wire cutting and twisting mechanism 75 is designed to be permanently mounted in convenient relation to the bundles of laths or other material to be bound, and in the present instance is shown as mounted upon one of the bundling arms 2. This device 80 comprises a base plate 6 which has one end thereof rigidly secured in some suitable manner as by means of the screws 7 to one of the bundling arms 2, the opposite end of the base plate being provided upon opposite sides thereof with wire receiving slots 8. These slots 8 are shown as arranged in substantial alinement with each other, and a shaft 9 extends through the base plate and is journaled therein at an intermediate 90 point between the inner ends of the slots. A rotating head 10 is rigid with one end of the shaft 9 and bears against one side of the base plate 6, while an operating handle 11 is rigidly applied to the opposite end of the 95 said shaft, any suitable means such as the set screw 12 being utilized for securing the handle to the shaft. This rotating head 10 is provided in opposite ends thereof with wire receiving slots 13 which are designed 100 to be turned into registry with the wire receiving slots 8 of the base plate 6. The inner ends of the slots 13 incline downwardly in opposite directions toward each other so that the said slots almost meet at the bottom 105 of the head, while at the top of the head

they merely have a depth corresponding to the depth of the wire receiving slots 8 of the base plate. Intersecting the wire receiving slot 13 at each end of the rotating head 5 and arranged in a plane at substantially right angles to the plane of the said slot is a slot 14 within which a retaining jaw 15 is mounted. These retaining jaws are carried by spring strips 16 applied to the exterior 10 of the head 10 on opposite sides thereof, and the inner ends of the jaws project into the wire receiving slots 13 so as to bear yielding- 15 against the wire and hold the same against accidental displacement.

15 For the purpose of enabling the rotating head 10 to be quickly turned into such a position that the slots 13 therein register with the slots 8 of the base plate, a depression 17 is provided in the top of the base 20 plate for engagement with a spring pressed plunger 18 carried by the handle 11. The end of the plunger 18 is rounded and the sides of the depression 17 are inclined so that the handle can be turned in either di- 25 rection by applying force thereto, although it will be held securely against accidental turning. It will also be observed that the sides of the base plate 6 are beveled at 19 so that the plunger 18 will not engage the 30 edges of the base plate and interfere with the rotation of the handle while the device is in operation.

In the operation of the device, the laths or other material are compressed in the usual 35 manner by the bundling machine and a suitable length of wire drawn from the reel 4. The handle 11 having been turned into such a position that the wire receiving slots of the rotary head are in alignment with the 40 wire receiving slots of the base plate and the plunger 18 in engagement with the depression 17, the wire is inserted in the slots 8 and 13 upon the far side of the device and then passed around the bundle, the free end 45 of the wire being inserted in the slots 8 and 13 upon the inner side of the device. The wire is thus crossed between the cutting and twisting device and the bundle and the initial movement of the handle causes the ro- 50 tary head 10 to act as a shear in connection with the base plate 6 and cut off or sever the wire, the said wire being held against accidental displacement from the slots 13 by means of the spring actuated retaining mem- 55 bers 15. The continued rotary movement of the head 10 brought about through the medium of the handle 11 operates to twist the ends of the wire, as is more clearly shown in Fig. 4. As the wire is twisted the ends 60 thereof are withdrawn from the rotary cutting and twisting head, so that by rotating the handle 11, the wire is first severed, then twisted, and finally discharged from the device. However, the weight of the bundle 65 would act to withdraw the extremities of

the wire from the device as soon as the bundle had been released through the medium of the treadle 3.

A very essential feature of the present invention resides in the fact that the wire is 70 cut off or severed before it is twisted, since the ends of the wire are then perfectly free and can be twisted with greater ease and facility than is the case where the wire remains connected to the reel until after the 75 twisting operation.

A further very important feature of the invention resides in the fact that the operator or attendant has nothing to do but 80 merely to turn the handle, this one movement acting as has been previously described to sever the wire, twist the same, and discharge it from the device. It will thus be obvious that the amount of time consumed in binding a bundle of laths or the like is much 85 less than where the operator must first turn a crank to twist the wire, and then operate an independent mechanism for cutting the wire.

It will be observed that a detail of practical importance in the construction of this device is that of providing the rotating head 10 with the diagonally opposite terminal projections 25 which act as guiding abutments to insure quick and accurate insertion of the wire in the opposite slots. 95

Having thus described the invention, what I claim as new and desire to secure by Letters Patent, is:—

1. In a wire cutting and twisting device, 100 the combination of a stationary member provided with wire receiving slots, a rotary member supported on the stationary member, and also provided with wire receiving slots adapted to initially register with those 105 of the stationary member and co-operating therewith to form a shear, and means for operating the rotary member so that this initial movement severs the wire ends and the continued rotation thereof effects a 110 twisting and final release of the wire ends.

2. In a wire cutting and twisting device, the combination of a stationary member, a rotary member mounted upon the stationary member so as to have a shearing action in 115 connection therewith and constructed to engage a wire, and retaining means upon the rotary member for preventing accidental disengagement of the wire therefrom.

3. In a wire cutting and twisting device, 120 the combination of a stationary member provided with wire-receiving slots, a rotary member mounted upon the stationary member so as to have a shearing action in connection therewith and provided with wire-receiving slots adapted to be turned into registry with the wire-receiving slots of the stationary member, retaining means for yieldingly holding the ends of a wire within 125 the wire-receiving slots of the rotary mem- 130

1. In a wire cutting and twisting device, the combination of a stationary member and means for turning the rotary member, and means for turning the rotary member.
2. In a wire cutting and twisting device, the combination of a stationary member formed with wire-receiving slots, a rotary member mounted upon the stationary member so as to have a shearing action in connection therewith and formed with wire receiving slots adapted to be turned into registry with the wire receiving slots of the stationary member, the said rotary member being also provided with a second set of slots intersecting the wire receiving slots, spring actuated jaws arranged within the second set of slots and projecting into the wire-receiving slots for preventing accidental disengagement of the wire, and means for turning the rotary member.
3. In a wire cutting and twisting device, the combination of a base plate provided upon opposite sides with wire receiving slots, a cutting and twisting head pivotally mounted upon one side of the base plate and provided in opposite ends thereof with wire receiving slots adapted to be turned into registry with the wire-receiving slots of the base plate, and a handle for turning the cutting and twisting head, the said cutting and twisting head having a shearing action in connection with the base plate so that the initial movement thereof severs the wire while continued movement thereof twists the ends of the wire.
4. In a wire cutting and twisting device, the combination of a base plate provided upon opposite sides thereof with wire-receiving slots, a shaft extending through the base plate and journaled therein between the inner ends of the slots, a cutting and twisting head rigid with one end of the shaft and provided in the ends thereof with wire-receiving slots adapted to register with the wire-receiving slots of the base plate, retaining means upon the head for preventing disengagement of the wire from the slots therein, and a handle applied to the opposite end of the shaft for rotating the cutting and twisting head, the said head having a shearing action in connection with the base plate so that the initial movement of the head acts to sever the wire while a continued movement thereof acts to twist the wire.
5. In a wire cutting and twisting device, the combination of a base plate provided upon opposite sides thereof with wire-receiving slots, a shaft extending through the base plate between the inner ends of the slots, a handle rigid with the shaft upon one side of the base plate, a cutting and twisting head rigid with the head upon the opposite side of the base plate and formed in its ends with wire-receiving slots adapted to register with the wire-receiving slots of the base plate, the said cutting and twisting head being also provided with a second set of slots intersecting the wire-receiving slots, and spring strips applied to the sides of the cutting and twisting head and formed with jaws which are received within the second-mentioned set of slots and project into the wire-receiving slots so as to have a yielding engagement with the wire and prevent accidental disengagement thereof from the cutting and twisting head, the said head having a shearing action with the base plate so that the initial movement of the head acts to sever the wire while a continued movement thereof acts to twist the wire.
6. In a device of the character described, the combination of a base plate provided with a wire receiving slot, a rotary head mounted upon the base plate and provided with a wire receiving slot adapted to register with the wire receiving slot of the base plate, a handle for turning the rotary head, and yielding means coöoperating with the handle to hold the rotary head against accidental movement when turned into such a position that the wire-receiving slot thereof registers with the wire-receiving slot of the base plate.
7. In a device of the character described, the combination of a base plate provided with a wire-receiving slot and also with a depression, a rotary head mounted upon the base plate and formed with a wire-receiving slot adapted to register with the wire-receiving slot of the base plate, a handle for turning the rotary head, and a spring-actuated plunger mounted upon the handle and adapted to engage the before-mentioned depression of the base plate for holding the rotary head against accidental movement when the said rotary head is turned into such a position that the wire-receiving slot therein registers with the wire-receiving slot of the base plate.
